UNITED STATES PATENT OFFICE.

ELMER R. POPE, OF HAMILTON, MASSACHUSETTS, ASSIGNOR TO UNITED SHOE MANUFACTURING CORPORATION, OF PATERSON, NEW JERSEY, A CORPORATION OF NEW JERSEY.

HEEL-NAILING MACHINE.

Application filed August 28, 1926. Serial No. 132,209.

This invention relates to heel nailing machines and more particularly to improved means for holding heels accurately in proper position to be nailed.

5 When a shoe heel is designed the points at which the heel attaching nails are to be driven are taken into consideration, the pattern formed by these points being called the nailing pattern of the heel. A number of factors 10 affect the determination of this nailing pattern, among them being the size and shape of the heel, and the location of the heel-seat nails, lasting tacks, and insole edge in the shoe to which the heel is to be attached. For best 15 results in heel attaching it is desirable that the nailing pattern of the heel to be located accurately in relation to the nail driving mechanism, and with some types of heels, such as rubber heels having nail anchoring washers 20 through which the nails must be driven, accurate location is a necessity.

Heretofore when great accuracy in the location of a heel relatively to nail driving mechanism has been required it has been 25 customary to provide a rigid holder, or form, consisting of a metal plate of approximately the same thickness as the heel and having through it an opening of exactly the same size and shape as the heel. This rigid holder, of 30 course, would fit heels of only one size and shape and when it was necessary to nail heels of another size or shape said holder had to be removed from the nailing machine and another holder of the right size and shape substituted for it.

An object of the present invention is to improve heel nailing machines by the provision of a heel holder of superior construction, which will greatly reduce the frequency with 40 which it is necessary to change holders or, under some conditions, eliminate changing at all, and will, at the same time, locate heels in the machine with a high degree of accuracy.

In the accomplishment of this object the 45 invention provides a heel holder in which the breast edges of heels of different sizes or shapes are located against fixed, spaced abutments by movable side and rear gages, which in the holder herein illustrated are operatively connected together in such a way that the 50 holder is expanded or contracted in a plurality of directions when the gages are moved. In the illustrative machine the holder, with

its fixed abutments, is located in a definite relation to the nail guiding conduits in the 55 nailing die and all heels within the range of the holder are definitely and accurately located in predetermined relation to said die.

The particular holder herein shown is especially useful in operating upon heels of 60 one common type, namely rubber heels in which a range of different sizes or shapes all have the same nailing pattern, located at substantially the same distance from the breast edges of the heels, the heels of the different 65 sizes included in the range differing from each other at their side and rear edges. In this instance, for example, the different heels will all be accurately located and held in correct 70 relation to the nailing die, both in respect to the nailing pattern of the heels and their outlines, without any attention being paid even to adjustments when changing from one size or shape of heel to another.

While one specific embodiment of the invention is herein shown and described in detail, it should be understood that various modifications may be made, within the scope of the appended claims, to adapt the invention to 75 the practical conditions under which it may be used.

In the accompanying drawings:—

Fig. 1 is a plan view of a heel holder embodying the invention;

Fig. 2 is a sectional view upon the line 85 II—II of Fig. 1, showing the holder in operative relation to the nailing die of a heelng machine; and

Fig. 3 is a sectional view of the holder upon the line III—III of Fig. 1.

In the drawings 10 indicates the nailing die of a heelng machine, having nail drivers 12 which operate in nail and driver guiding conduits 14 which are arranged in a fixed nailing pattern. This construction is well known in 90 heelng machines and reference may be had to United States Letters Patent No. 1,365,802, granted Jan. 18, 1921, on application of J. F. Standish, for a more complete disclosure of such a machine. The heel holder herein 100 illustrated is so designed that it may be readily substituted for the heel holding form or ring in the form holder disclosed in the said patent.

A plate 16 having a central opening 18 is 105 provided at its sides with ledges 20 adapted to

be inserted in suitable guides in the form holder of a heelng machine, whereby the plate 16 is accurately positioned and held in definite relation to the nailing die.

5. At the breast side of the opening 18 there are provided two fixed, spaced abutments 22 arranged to be engaged by the breast edge of a heel near its side edges, the locations of said abutments being such that heels will be 10 uniformly positioned irrespective of slight differences in the curvature of their breast edges.

15 A rear gage 24 is arranged to slide forwardly and rearwardly, toward and from the breast gage constituted by the abutments 22, in under-cut guides 26 formed in the plate 16. Compression springs 28, housed in recesses 30 in the plate, bear against pins 32 which are screwed into the rear gage 24, as 20 shown in Fig. 3, and tend to move the rear gage forwardly toward the breast gage.

25 Side gages 34 are pivotally movable about fixed centers 36 inwardly and outwardly of the holder, and are connected by slots 38 and pins 40 with forward extensions 42 of the rear gage 24. The result of the pivotal mounting of the side gages and their pin-and-slot connections to the rear gage is that the side gages are moved by the rear gage as the latter moves toward or from the breast gage, providing an expandible holder which is normally contracted by the yielding springs 28.

30 The design and proportions of the parts are such that the inward and outward movements of the side gages 34 are less than the forward and rearward movements of the rear gage 24, since heels of different sizes differ more in length than in width. It will, therefore, be apparent that, by reason 35 of the structure and connections above described, outward movement of any one of the movable gages will cause the holder to be expanded unequally in a plurality of directions. The dotted lines 44, 46 indicate two heels of different sizes but having the same nailing pattern located in the same relation to the heel breast. From the foregoing it will be apparent that such heels of different sizes will be positively and 40 definitely located in proper relation to the nailing die with great accuracy and that the frequency with which it is necessary to change heel holders in the ordinary course of work will be greatly reduced, since two or 45 more sizes or shapes of heels are frequently made with the same nailing.

50 Having described my invention, what I claim as new and desire to be secured by Letters Patent of the United States is:

60 1. A heel holder comprising fixed, spaced abutments arranged to be engaged by a curved heel breast at separated points, a rear gage movable toward said abutments to engage the rear edge of the heel, and side gages

connected to the rear gage and movable 65 thereby into engagement with the side edges of the heel.

2. A heel holder comprising fixed, spaced abutments arranged to be engaged by a curved heel breast at separated points, a rear 70 gage slidable toward said abutments, and side gages pivotally movable about fixed centers into engagement with a heel held between the breast engaging abutments and the rear gage. 75

3. A heel holder comprising fixed, spaced, heel-breast engaging abutments, a rear gage slidable toward said abutments, and side gages pivotally movable about fixed centers 80 into engagement with a heel held between the breast engaging abutments and the rear gage, said side gages being connected to, and moved by, the rear gage.

4. A heel holder comprising fixed, spaced, heel-breast engaging abutments, a rear gage 85 movable forwardly toward said abutments, and inwardly movable side gages operatively connected to the rear gage to be moved thereby through less distances than that through which the rear gage moves. 90

5. In a heel nailing machine, the combination of a nailing die having a group of nail guiding conduits arranged in a fixed nailing pattern, and a holder for heels of different sizes but all having said nailing pattern, 95 said holder having means in fixed relation to the nailing die for engaging a curved heel breast at two separated points spaced from the sides of the heel, and movable means for engaging the side and rear edges of heels of 100 different widths and lengths and pressing said heels against said breast engaging means.

6. A heel holder comprising a fixed breast gage, a movable rear gage which is spring-pressed toward the breast gage, and movable 105 side gages connected to the rear gage to be moved inwardly when the rear gage moves forwardly and outwardly when the rear gage is moved rearwardly by pressing a heel 110 against it.

7. An expandible heel holder having gages for the breast, sides and rear edges of a heel, yielding means for normally contracting the holder, and connections between certain of 115 said gages whereby outward movement of one gage will positively expand the holder in a plurality of directions.

8. An expandible heel holder having gages for the breast, sides and rear edges of a heel, 120 yielding means for normally contracting the holder, and connections between certain of said gages whereby outward movement of one gage will positively expand the holder unequally in a plurality of directions. 125

In testimony whereof I have signed my name to this specification.

ELMER R. POPE.
